(57) **CLAIM**

The ornamental design for a spur bottle opener key chain, as shown and described.

DESCRIPTION

FIG. 1 is a left side perspective view of the spur bottle opener key chain of the present invention showing the Applicant's new design;

FIG. 2 is a left side elevation view of the spur bottle opener key chain of FIG. 1;

FIG. 3 is a right side elevation view of the spur bottle opener key chain of FIG. 1;

FIG. 4 is a back elevation view of the spur bottle opener key chain of FIG. 1;

FIG. 5 is a front elevation view of the spur bottle opener key chain of FIG. 1;

FIG. 6 is a top plan view of the spur bottle opener key chain of FIG. 1; and,

FIG. 7 is a bottom plan view of the spur bottle opener key chain of FIG. 1.

The broken line showing the key ring in FIGS. 1 through 7 is for illustrative purposes only and forms no part of the claimed design.
